US0D1072446S

(12) United States Design Patent (10) Patent No.: US D1,072,446 S
(45) Date of Patent:  Apr. 29, 2025

(54) FOOTWEAR

(71) Applicant: Target Brands, Inc., Minneapolis, MN (US)

(72) Inventor: Austyn Dunham, Minneapolis, MN (US)

(73) Assignee: Target Brands, Inc., Minneapolis, MN (US)

() Term: 15 Years

(21) Appl. No.: 29/922,050

(22) Filed: Dec. 20, 2023

Related U.S. Application Data

(62) Division of application No. 29/754,385, filed on Oct. 9, 2020, now Pat. No. Des. 1,015,706.

(57) CLAIM

The ornamental design for a footwear as shown and described.

DESCRIPTION

FIG. 1 is a front, top and right side perspective view of an embodiment of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a back, bottom, and left side perspective view thereof.

The broken lines in the drawings show portions that form no part of the claimed design.

1 Claim, 6 Drawing Sheets
